TIMING DEVICE

Thomas A. Killman and Robert Thomas Killman,
Nashville, Tenn., assignor to Dazey Churn &
Mfg. Co., a corporation of Missouri

Application September 9, 1932, Serial No. 632,330

8 Claims. (Cl. 58—28)

This invention relates to a timing device operated by an electric current.

The invention is of such a nature that it may be used for many different commercial purposes and, in the embodiments specifically illustrated in the drawings and described in this specification, it is operated to intermittently close and open a switch for an electric circuit, whereby a lamp may be alternately flashed and extinguished. 5

10 In an embodiment illustrated in our co-pending application Serial No. 632,331, filed of even date herewith, it may be used for operating a clock or other mechanism where constant rotation is required, but where only a small torque is necessary.

One of the objects of this invention is to provide a device operable by an electric circuit which will produce accurately uniform oscillations.

Another object of the invention is to provide 20 an automatic switch for an electric circuit which will alternately and successively, with regularity, make and break the circuit.

Another object of the invention is to provide 25 a two-way electric switch which may be operated by an oscillating member to connect an electric circuit alternately in two arrangements.

Another object of this invention is to provide 30 a device having an oscillating member receiving impulses successively from two electro-magnets, and an automatic switch for the circuit supplying the electro-magnets, with means for bringing the oscillating member to rest upon cessation of current in a position in which one of the electro-magnets is connected in circuit by said automatic 35 switch.

Other and specific objects will appear from the following detail description, taken in connection with the accompanying drawings, in which—

Fig. 1 is a plan view of the device.

40 Fig. 2 is a side elevation partly in section.

Fig. 3 is a side elevation partly in section taken at an angle of 90° from the position of Fig. 2.

Fig. 4 is a vertical section on line 4—4, Fig. 1.

Fig. 5 is a vertical section on line 5—5, Fig. 1.

45 Fig. 6 is a cross section on line 6—6, Fig. 3.

Fig. 7 is a detail sectional view on line 7—7, Fig. 1.

Fig. 8 is a detail sectional view on line 8—8, Fig. 7, with projections showing the position of parts at different moments of operation.

50 Fig. 9 is a plan view similar to Fig. 1 with the parts shown in different operative relationships.

Fig. 10 is a circuit diagram.

The device includes generally an oscillating balance which, in the embodiment specifically

illustrated, is adapted by its oscillations to make and break an electric circuit and is useful in this embodiment to intermittently and in accurately timed relationship cause an electric lamp to flash. The balance includes magnetic material, that is iron or steel, by reason of which it may act as an armature. The balance is provided with a spring whereby it may be caused to oscillate, and a pair of electro-magnets are provided to give impulses to the balance. A switch 5 is provided to be operated by the oscillation of the balance, whereby the electro-magnets are selectively and alternately connected in an electric circuit. The electro-magnets are positioned and connected in such a manner that the attractions of the electro-magnets for the balance are always in the direction in which the balance has been moving.

Having described the invention generally, a detail description of a preferred construction of 20 the invention and its embodiment in a device for some uses now follows.

A housing includes a cylindrical wall 1, a bottom wall 2 and a cover plate 3. A frame comprising uprights 4, a top strap 5 and a bottom member 6 is secured to the bottom wall 2 of the housing with an electrically non-conductive plate 7 interposed therebetween. The insulating plate 7 is secured to the wall 2 by screws 8 and the bottom member 6 is secured to the plate 7 by screws 9.

A balance staff 10 is journalled at its lower end in the frame member 6 and at its top end in the frame member 5. A balance 11 is fastened to the staff. A spring 12 is arranged to reverse the 35 direction of oscillation of the balance 11 after an impulse has been given to it. The spring 12 is fastened at its upper end at 13 to a collar 14, secured to the staff 10, and the spring is secured at its lower end, as shown at 15, to an adjustable 40 member 16 which in turn is secured to the frame member 6 by screws 17 passing through slots 18 in the member 16. The balance 11 carries or includes magnetic material, that is iron or steel. In the particular form illustrated, an iron weight 45 19 is secured to each end of the balance 11 by a screw 20. Thus the balance may also act as an armature when placed in the field of an electro-magnet. Two electro-magnets 21 and 22 are provided, positioned in the paths respectively of 50 the weights 19, and adapted, as will hereafter be described, to alternately attract the balance and give it an impulse always in the direction in which the balance is oscillating. Thus, referring to Fig. 1, when the balance 11 is moving in a 55

clockwise direction the electro-magnet 22 is energized and when the balance is moving in a counter-clockwise direction the magnet 21 is energized. Means for connecting the magnets 21 and 5 22 selectively in circuit will presently be described.

A battery 23 has one pole connected to the ground as shown at 24, Fig. 10, and has its other pole connected by a lead 25 to a binding post 26, 10 connected to but insulated from the cylindrical wall 1, an insulating washer 27 being positioned between the post 26 and the wall 1. The binding post 26 and, therefore, one pole of the battery 23 is electrically connected to the balance 11 by a 15 wire 28 connected between the post 26 and the frame, the lead being attached as shown in the drawings to one of the uprights 4. One side of each of the windings of the electro-magnets 21 and 22 is connected to a ground by a lead 29. 20 The lead 29 is attached to a binding post 30 secured to the cylindrical member 1 which has a lead 31 to a ground. The binding post 30 need not be insulated from the wall 1. It will thus be seen that the electro-magnets 21 and 22 may 25 be selectively energized by selectively connecting the balance 11 to leads for the magnets.

This selective connection of the magnets 21 and 22 is accomplished by a new and ingenious switch mechanism which will now be described.

30 An overhanging arm 32 is secured to the plate 7 by a clamp 33. This overhanging arm includes two superimposed conductive strips 34 and 35 insulated from each other by an insulating strip 36. The lower strip 34 is connected by a lead 37 to the winding of the electro-magnet 21 and the upper strip 35 is connected by a lead 38 to the winding of the electro-magnet 22.

The overhanging arm or bracket 32 is of the form best shown in Fig. 7 and includes an upper 40 end portion 39, Fig. 7, which extends in a line parallel to the plate 7, that is, in a horizontal line but in a plane tilted slightly from the horizontal, as clearly shown in Fig. 8. The purpose of this tilting is, as shown in Fig. 8, to permit a movable 45 contact 40 which is secured to and oscillates with the balance 11 to brush the upper strip 35 on its clockwise movement and the bottom strip 34 on its counter-clockwise movement.

The contact 40 is supported at the outer end 50 of a resilient arm, comprising a pair of resilient strips 41 supported at their inner ends by a bracket 42 on the balance 11. The arm supporting the contact 40 is bifurcated, as explained, in order to provide resiliency and at the same time to dampen the vibration. The strips 41 are secured together at their inner ends and may or may not be secured at their outer ends. When separated the lower strip 41 acts as a support for the contact 40 and the upper strip 41 acts merely as a 55 dampener.

The spring adjusting member 16 is set in such a manner that the spring 12 will have a tendency to cause the balance to come to rest in a position, as shown in Fig. 1, in which the contact 40 is in engagement with the arm 32, either on the lower strip 34 or on the upper strip 35, according to chance. Now with the balance 11 at rest and with the contact 40 engaging the strip 35, if, for 60 instance, as shown in Fig. 1, the circuit is completed as illustrated and the lead 25 is connected to one pole of the battery, ground connections being made as heretofore explained, the electro-magnet 22 will be energized and the balance will 65 be moved in a clockwise direction. This move- 70

ment will be very slight until contact is broken between the point 40 and the strip 35, but the urge will be sufficient to move the balance 11 to the position shown in full lines, Fig. 9. When the balance has assumed this position the tension 5 of the spring will have caused it to come to rest and will return the balance in the opposite or a counter-clockwise direction. Upon this return in a counter-clockwise direction, the balance 11 will come again to the position shown in Fig. 1, 10 but with the contact 40 below the extension 39, at which time the winding of the electro-magnet 21 will be placed in circuit and its flux will have a tendency to urge the balance in the direction in which it is moving, but this contact will be 15 maintained only momentarily. The balance 11 will then move only to a position shown in broken lines, Fig. 9. Thereupon the spring 12 will again return the balance in a clockwise direction and contact will be made between the point 40 and the 20 strip 35. The cycle of operation will be continuously repeated as long as the device is properly connected to a source of current supply. The apparatus described has many useful purposes, one of which we have illustrated, described and 25 claimed in my application, Serial No. 632,331, filed of even date herewith. Another useful purpose is illustrated in the embodiment of this application in which the oscillation of the balance 11 is caused to make and break an electric circuit 30 which may be used, for instance, to flash an electric lamp. Additional mechanism which we have illustrated and which is useful for the purpose of making and breaking an electric circuit will now be described.

35 A non-conductive disc 43 is secured to the balance 11 and a conductive plate 44 is placed on top thereof and electrically connected to the staff 10. A brush 45, adapted to make contact with the plate 44, is supported by a bracket 46, secured to the frame member 5 by a screw 47, but the brush 45 is insulated from the frame by a washer 48. The brush 45 is connected by a lead 49 to a binding post 50 on the cylindrical member 1, and the binding post is insulated from the cylindrical member by an insulating washer 51. A lead 52, secured to the binding post 51, may be connected to a lamp 53, the other side of the lamp being connected to a ground by a lead 54.

40 As best shown in Figs. 1 and 9, the brush 45 will make contact with the plate 44 whenever the balance 11 is oscillated to the extent as intended and shown in Fig. 9. In the particular embodiment illustrated, this contact is made twice during each cycle of oscillation, that is, 45 contact will be made between the brush 45 and the conductive plate 44 when the balance 11 is at or near each end of its path. It will be obvious that the device may be constructed to make contact either once or twice during each cycle, 50 as this is determined by the arc in which the balance oscillates and the proportioning of the sector plate 44.

55 As previously explained, the spring 12 is so adjusted by the member 16 that the balance 11, 60 in the absence of current, assumes a position as shown in Fig. 1, and in this position contact between the brush 45 and the plate 44 is broken and the lamp circuit is, therefore, open.

65 It will be obvious from the known laws of 70 physics that frequency of vibration will depend upon the weight of the balance 11, the length of the arms of the balance, the strength of the spring and its moment of vibration, and hence the frequency of the vibration of the balance 11 75

may be altered by changing any of these factors.

Parts of the invention may be used without the whole and various changes may be made in the details of construction, and in the mode of applying the invention to useful purposes, within the scope of the appended claims, without departing from the spirit of this invention.

We claim:

1. In a timing device including an oscillating member adapted to oscillate in uniform timed succession, and a pair of electro-magnets positioned and adapted to intermittently and alternately attract and thereby propel said member, the combination including a fixed arm having a contact on each side thereof insulated from each other and connected respectively to said electro-magnets, a resilient member extending from and fixed to said oscillating member and carrying an electrical contact at its outer end, said arm being arranged in the path of the outer end of said resilient member and being inclined with respect to the plane of oscillation thereof whereby the outer end of said resilient member makes electrical contact on one side of the arm when the oscillation is in one direction and on the opposite side when the oscillation is in the opposite direction.
2. In a device of the kind described having a spring balance, the combination including an armature mounted on and oscillated by the balance, a pair of spaced electromagnets each having a core with its end adjacent the path of oscillation of the armature, and a switch comprising a resilient member extending from and fixed to the balance and carrying a contact at its outer end and a fixed arm having contacts on both sides respectively thereof, insulated from each other and connected respectively to the electromagnets, said arm being positioned midway in the path of the contact on said member and being inclined with respect to the plane of oscillation whereby the contact on said member will wipe the contact on one side of the arm when the oscillation is in one direction and on the opposite side when the oscillation is in the opposite direction, and in the absence of power will come to rest in engagement with one or the other of said contacts.
3. A device of the kind described, including a frame, an oscillator mounted thereon for movement in two directions from a given point, a spring, means connecting said spring to said frame and said oscillator to urge the latter to the given point, said connecting means including a disc-like element to which said spring is connected, said element being slotted, and means engaging said frame to said element through said slotted portion thereof whereby said element may be adjusted relative to said frame and secured in adjusted position.
4. A device of the kind described, including an oscillator, two electrically energized devices for producing the force to operate said oscillator, a circuit for each of said devices, means for connecting said circuits to said devices including a switch, said switch having a contactor on said oscillator to swing therewith and a member with which said contactor cooperates, said member and said contactor being sloped relative to the plane of oscillation, and one of them comprising a unit having two conducting faces on opposite sides thereof and insulation therebetween, one face being connected to each circuit whereby as said contactor swings in one direction it will connect with one of said conducting elements,

and as it swings in the other direction, it will connect with the other.

5. In a device of the kind described, a pair of spaced electromagnets, an armature having a pivot and two arms extending therefrom, each arm having a permeable portion thereon, said magnets being spaced from said pivot, and with the pivot including a different angle from that included between the two arms, whereby when one of said arms is centrally over its magnet the other will be displaced from the other magnet, means urging said armature to a normal position wherein the arms are equally spaced from the magnets and within the extent of their fields, electrical circuits for said magnets, switch means in said circuits, and actuated by said armature to energize one magnet in one direction of oscillation of the armature and the other magnet in the other direction of such oscillation, said switch being operable to energize one of said magnets when the armature is in normal position.

6. In a device of the kind described, a pair of spaced electromagnets, an oscillatory armature having a pivot and two arms extending therefrom, each arm having a permeable portion thereon, said magnets being spaced from said pivot and with the same including an angle different from the angle included between the two arms, means urging said armature to a normal position wherein said arms are equally spaced from and within the extent of the fields of the respective magnets, a circuit for said magnets including a two way switch, said switch being closed one way as one arm moves toward its magnet to energize said magnet and accelerate the oscillation in that direction, and being closed the other way as the other arm moves toward its magnet to energize said magnet and accelerate the oscillation in the other direction.

7. In a device of the kind described, a member movable in two directions in a fixed path, two circuits, a means energized by each circuit, a switch in said circuits, said switch including a member having its faces formed as contact surfaces insulated from each other sloped relative to the plane of movement of the movable member at a predetermined point, one for each circuit, and a member cooperable with one or the other of said surfaces, one of said switch members being mounted on the movable member and one being fixed relative thereto, whereby as said movable member moves in one direction the cooperating member closes with one of said sloping surfaces, and when it moves in the other direction, it closes with the other surface.

8. In a mechanism of the kind described having a spring balance, the combination including armature means adapted to be oscillated in a fixed plane and by the spring balance, a pair of spaced electromagnets each having its core normal to said plane and adjacent the path of the armature means in its oscillation and said electromagnets being adapted selectively to influence said armature means, a circuit for each of the electromagnets having a switch for each of the circuits, said switches being operable by the balance separately to complete the respective circuits of the electromagnets to a source of power, each during a relatively small portion of an oscillation and when the armature means is moving toward the electromagnet the circuit of which is thus completed, and at substantially the middle portion of such oscillation.

THOMAS A. KILLMAN.

ROBERT THOMAS KILLMAN. 75
